ADJUSTABLE CLASP

Herman Vizner, New York, N. Y., assignor to D. Ornstein & Sons Corp., a corporation of New York

Application February 7, 1947, Serial No. 727,238

1 Claim. (Cl. 24—206)

1

This invention relates to fastening devices and, more particularly, to adjustable clasps that incorporate several new and novel features.

My principal objective was to design a clasp that could be utilized as fastening means on clothing, watch bands, belts or on any other manufactured articles where buckles or similar devices are used. The result of this objective is my present invention which comprises an adjustable clasp that features cam operating locking means.

A further advantage is that my device is simple in construction, inexpensive to produce, and has a minimum of parts. Each of the three members comprising the clasp is capable of being stamped and shaped from single pieces of metal which can then be easily and quickly assembled together to form a clasp.

Another feature is that the clasp is capable of being adjusted to the desired length and then, by slight movement of the locking member, the co-acting parts of the clasp are firmly and securely locked together. Through the functioning of the cam locking means, an effective locking engagement is secured which prevents any slippage and maintains the clasp in its selected position. A slight movement of the locking cam in the opposite direction assures a quick and ready release with a minimum of effort.

Further advantages and unique features of my device will be apparent as I proceed with the description.

Referring to the drawings—

Figure 1 shows a plan view of the preferred form of my device in locked position;

Fig. 2 shows a view on line 2—2 of Fig. 1;

Fig. 3 shows a view on line 3—3 of Fig. 2;

Fig. 4 shows a view similar to Fig. 2 with the tongue disengaged from the locking member;

Fig. 5 shows a plan view of the various parts of the clasp before being assembled;

Fig. 6 shows a view on line 6—6 of Fig. 5;

Fig. 7 shows a plan view of a modified form of my invention;

Fig. 8 shows a view on line 8—8 of Fig. 7;

Fig. 9 shows a view on line 9—9 of Fig. 10;

Fig. 10 shows a plan view, partially in section, of another modification of my invention; and

Fig. 11 shows a partial perspective view of the locking means of the device shown in Figs. 9 and 10.

In Figures 1 through 6, I have shown the preferred form of my adjustable clasp A which can be manufactured from lightweight metal or any other material that will adequately serve

2

the purpose. Basically, the clasp is composed of three main parts, namely, a tongue 20, a locking member 30 and a gripping member 40.

Tongue 20 comprises a flat piece of metal 21 with a loop 22 at one end to which can be secured a strap 23 or other material that is to be fastened. The center portion of the tongue 20 is equipped with a plurality of corrugations with alternate ridges 24 and grooves 25 extending above and below the surface of the tongue 20. Although I have specified corrugations, it is realized that the same effect might be secured by alternately welding small pieces of wire to both sides of the tongue 20 which would serve the same purpose.

The locking member 30 also serves as a housing for the clasp and its walls enclose the other two members on three sides, terminating on the bottom in two flanges 31 which support the gripping member 40. The top surface 35 of the locking member 30 has an extension which is bent back upon itself in the shape of an U to form a loop 33. This extension extends inside of the locking member and constitutes the locking plate 32. The plate 32 is inclined slightly toward the top surface 35 leaving a space 34 between the plate 32 and the top surface 35. The plate 32 is narrow at the loop 33 so that it will be free to move between the flanges 45 of the gripping member 40. The major portion of the plate 32 widens out a short distance from the loop 33 so that its sides extend parallel to the sides of the locking member 30 and have sufficient clearance from the inner walls of the gripping member 40 to allow for unobstructed movement.

The gripping member 40 can be made of a single strip of metal which is bent back upon itself approximately midway its length in the form of an U with upper and lower gripping plates 41 and 42, respectively. The resultant loop 41 can be utilized to attach a strap or other material to be fastened. The central portion of the lower gripping plate 42 is equipped with a plurality of corrugations 43 similar to the tongue 20. The upper gripping plate 41 is also equipped with corrugations 48. The outside edges of the lower gripping plate 42 are bent upward at right angles to form sides 44 and top flanges 45. Sufficient space is allowed between the flanges 45 for the unobstructed movement of the locking plate 32. Positioned on each of the flanges 45 near the open end of the gripping member 40 are downward extending cams 46.

To operate the clasp, the locking member 30 and gripping member 40 are assembled as shown in

Fig. 4 so that the plate 32 rides above the corrugations 48 of the upper gripping plate 47. The tongue 20 is then inserted between the upper gripping plate 47 and the lower gripping plate 42 of the gripping member 40. The upper 47 and lower 42 gripping plates are held close together by spring tension with the result that when the tongue 20 is inserted between them the spring tension of the plates 47 and 42 is sufficient to hold the tongue 20 at the desired adjustment until the locking member 30 is operated. The locking member 30 is then moved a short distance in the direction of the strap 23 which will force the plate 32 beneath the cams 46. This will cause the corrugations 48 and 43 of the upper and lower gripping plates 47 and 42 to co-act with the corrugations of the tongue 20 resulting in the tongue being firmly gripped from both sides making a secure locking engagement. To release the tongue 20, it is merely necessary to slide the locking member 30 toward strap 49 which will result in the plate 32 becoming disengaged from the cam 46. This will allow the upper 47 and lower 42 gripping plates to move apart, enabling the tongue 20 to be withdrawn.

In Figures 7 and 8 I have shown a further modification of my device which, with few exceptions, functions in the same manner as the preferred form previously described. The modified clasp B has a tongue member 50 with corrugations 51 and a locking member 55 with a plate 56. Both the tongue 50 and the locking member 55 are similar in construction and function to those described in clasp A. The gripping member 60 in clasp B has only one gripping plate 61 which is equipped with corrugations 62 and which is located at the bottom of the gripping member 60. The operation of the clasp B is the same as that previously described so that when locking member 55 is moved toward the loop 52, the plate 56, in sliding under the cam 63, forces the corrugations of the tongue 50 and gripping plate 61 into locking engagement. A movement of the plate 56 in the opposite direction releases the tongue 50 enabling it to be withdrawn. This modification has the additional feature of greater range of adjustment in that the tongue 50 may slide all the way through the opening between the plate 56 and the gripping plate 61 as its movement is not restricted as in the case of clasp A which has loop 41.

Figures 8 to 10 illustrate another modification which functions on the same principle as clasp A and B but incorporates a slightly different construction. Clasp C has a tongue member 70 which is composed of a flat piece of metal with opposite edges 71 and 72 being serrated in a saw-tooth manner. One end of the tongue 70 is adapted to be inserted into the gripping member and the opposite end is equipped with a loop 73 for attachment to a strap or other article. The gripping member 80 has a base plate 81 with opposite edges being bent upward and over to form channels 82 in which the locking rod 93 is positioned. At approximately the center of the member 90, on opposite sides, an additional portion of the edges of base plate 81 are bent downward again so that they are flush with the base plate 81 forming arms 83. Positioned near one end of each arm 83 is a projection 84 which is adapted

to engage in the notches of the serrated edges 71 and 72 of the tongue 70.

The locking member 90 is comprised of a single metal plate 91 with opposite edges shaped around and underneath the gripping member 80 to form a housing and furnish support for the gripping member. One end of the metal plate 91 is bent to form a loop 92 in which is positioned the locking rod 93. The locking rod 93 is U-shaped with the open end facing the tongue 70 and extending down either side of the gripping member 80 in the channels 82. The rod 93 is positioned behind the arms 83 and in their open position, as shown in Fig. 11, the arms 83 are free to move in and out as the tongue 70 is inserted and the projections 84 engage the notches of the serrated edges 71 and 72. When the desired adjustment has been obtained, the locking member 90 is moved toward the loop 73. This movement causes the locking rod 93 to slide behind the arms 83 preventing any lateral movement of the arms 83 and thereby securely locking the projections 84 into the notched edges of the tongue 70. To release the tongue 70, the locking member 90 is moved in the opposite direction which causes the locking rod 93 to withdraw from behind the arms 83 allowing free lateral movement of the projections 84 which allows the tongue 70 to be withdrawn.

Although I have shown my device consisting of flat plates, it should be realized that it would function equally as well where the plate members are curved to adapt them to the shape of a wrist or some other curved object. While the invention has been described in detail with respect to a present preferred form which it may assume, it is not to be limited to such details and form since many changes and modifications may be made in the invention without departing from the spirit and scope of the invention in its broadest aspects. Hence, it is desired to cover any and all forms and modifications of the invention which may come within the range or scope of the appended claim.

I claim:

An adjustable clasp including a tongue, a gripping member and a locking member, said tongue equipped with serrated edges, said gripping member comprising a plate whose opposite edges are shaped to form channels, the inner walls of said channels comprising arms on which are positioned projections adapted to co-act with the serrated edges of said tongue, a slidably operated locking member equipped with a locking rod adapted to move in said channels, movement of said locking member in one direction causing said locking rod to hold said projections in locking engagement with the serrated edges of said tongue when said tongue is disposed between said projections.
